AUTOMATIC RECORD CHANGER

Donald R. De Tar, Stratford, Conn., assignor to
General Electric Company, a corporation of New
York

Application September 19, 1940, Serial No. 357,426

16 Claims. (Cl. 274—10)

My invention relates to automatic record changing phonographs.

One of the objects of my invention is to provide an improved automatic record changing phonograph capable of playing records of different diameters in succession without attention of the operator.

A further object of my invention is to provide in such a phonograph a material simplification of the mechanism employed whereby the adaptability of the phonograph to large scale commercial production is improved.

Further objects of my invention relate to improvements in the record changer actuating mechanism, tone arm actuation mechanism, and, in particular, to improved stop mechanism for the tone arm whereby it is stopped in a position determined by the diameter of the next record to be played.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawings in which Fig. 1 represents a side view partly in section of my invention; Fig. 2 represents a top view with portions cut away; Fig. 3 is an exploded view; Figs. 4, 5, and 7 and 8 represent modifications, and Fig. 6 illustrates a detail of Fig. 5.

Referring to Fig. 1, I have indicated therein a phonograph having a turntable 1, arranged for rotation about a central shaft 2 which is journaled in a bearing 3 carried by a chassis member 4. The turntable 1 is driven by means of a motor 5 which is provided with a pinion 6 indicated in dotted lines underneath the turntable 1. This pinion cooperates with the inner surface of a peripheral flange 7 about the circumference of the turntable.

Above the turntable 1 is positioned a stack of records 8 through the centers of which extend an extension shaft 9, which has a screw threaded, or dowel, connection with the shaft 2 upon which the turntable 1 is carried, whereby the stack of records 8 is centered with respect to the turntable. This stack may include records of different diameters indiscriminately arranged. As illustrated, the lower three records are of smaller diameter while the upper two are of larger diameter.

This stack of records is supported in a magazine, which is made up of two or more columns 10 and 11 on either side of the turntable. These columns are hollow and have extending therethrough shafts of which the shaft 12 in column 10 is indicated on the drawings. These shafts 12 at their upper end carry cylindrical sleeves 13

to which are attached platens 14 and 15. These platens are indicated in Fig. 1 but will be better described hereinafter. The records in the magazine normally rest upon the platen 15. During the discharge of the records, however, shafts 12 are caused to rotate thereby rotating the platens 15 out from underneath the records thereby permitting the bottom record of the stack to fall upon the turntable. Prior to the discharge of the bottom record, however, the platens 14 move in between the two bottom records so that the remaining records in the stack are supported upon the platens 14. The shafts 12 are then rotated to their initial position in which the stack is again supported by the platens 15.

The tone arm 16, provided with a stylus 17, is shown in the position which it assumes when the last record in the stack has been played. When the phonograph is started as by means of a handle 18, this tone arm automatically moves to the starting position of the record to be played, this position having been determined by a finger 19 which is rotated by the record discharge mechanism to a position such that it engages the periphery of the bottom record of the stack just before it is discharged from the magazine. In this way it positions a tone arm stop mechanism, later to be described, whereby the tone arm is stopped at a position corresponding to the diameter of the record to be played.

The record changing mechanism and the tone arm are operated from a horizontal cam shaft 20 beneath the chassis which cam shaft is driven through a clutch 21 from the shaft 2, upon which the turntable is mounted, through a worm 22 and a worm wheel 23. The clutch 21 is closed by operation of a lever 24 either through throwing of the handle 18 or by means of lever 100 after a record has been played. When this occurs the shaft 20 is driven through one complete revolution.

This shaft is provided with two cams 26 and 27. On the periphery of cam 26 rides the lower end of a vertical rod 28. This rod 28 extends upward through a sleeve 28' which is supported in a bushing, not shown in the drawings, and its upper end supports the tone arm at a point intermediate its ends and forms a pivot about which the tone arm swings in its horizontal movement. This rod 28 is moved upward by the cam 26 and thus lifts the tone arm from the position in which it is shown, if it be in that position, or from the record if it be on the record.

Cam 27 is straddled by a rocker member 29, which is rigidly attached to a shaft 30. The left end of this shaft 30 is provided with an arm 31, which is connected through a link 32 with a rocker lever 34, the opposite ends of which are connected through suitable linkage to the shafts 12. Thus, upon rotation of the shaft 20 cam 26

first lifts the tone arm, cam 27 then rocks the rocker member 29 counterclockwise thereby rotating arm 31 counterclockwise and causing movement of the lever 34, which in turn rotates the shafts 12 to discharge a record. Later, after the record has been discharged, rocker 29 and bench arm 34 and shafts 12 return to their initial position and, subsequently, the tone arm is lowered.

Fig. 2 is a horizontal view of the apparatus with the records and turntable cut away to illustrate more clearly the tone arm positioning mechanism. This mechanism comprises a disk 35 mounted upon column 11 of Fig. 1 for rotation about shaft 12 and to which is attached the finger 19 mentioned in connection with Fig. 1. This finger 19 and disk 35 are connected to the shaft 12 through a drag connection comprising spring 37. Of course, a suitable frictional drive connection might be used. In this way, when shaft 12 and platens 15 and 14 are rotated clockwise, as seen in Fig. 2, to discharge a record, finger 19 and disk 35 are rotated clockwise until the end of finger 19 engages the periphery of the record about to be discharged. It is thus restrained from further movement although shaft 12 and the platens 14 and 15 continue their rotation until the record is discharged. In this way disk 35 is positioned in accordance with the diameter of the next record to be discharged from the stack.

This disk 35 has three different radii, one being a small radius, as indicated at 36, corresponding to the smallest record to be played; another being somewhat larger, as indicated at 39, corresponds to a larger record to be played; and a third being still larger, as indicated at 38, corresponds to the condition in which the magazine is empty.

Adjacent the disk 35 is a tone arm stop lever 40 pivoted for rotation about a pivot 41 under influence of a spring 42 but, in the condition shown, restrained from such rotation by means of a pawl 43, which engages in one or another of three notches in one end of the lever 40. This pawl is held in engagement with one of these notches by means of a spring 44.

Just prior to the discharge of a record, pawl 43 is actuated through means not shown in Fig. 2 to release stop lever 40 whereby this lever moves under influence of spring 42. It is provided with a detent 45 which then engages the periphery of disk 35 to stop the movement of lever 40. Pawl 43 then re-engages the end of lever 40 and holds it in its new position determined by the radius of disk 35 adjacent detent 45, which position has been determined by finger 19 engaging the periphery of the record to be discharged from the magazine.

The right end of the lever 40 is provided with three notches 46, 47 and 48. The tone arm, after being lifted, is moved toward the record by means of a spring 49 until pawl 50 engages one of the notches 46, 47 and 48. It is shown in the notch 48 since it is assumed that the machine stopped after playing the last record. During operation it engages the notch 47 when the next record to be played is of a large diameter and the notch 46 when the next record to be played is of small diameter. In this way the extent of its inward movement is determined by the diameter of the next record to be played.

Fig. 3 is an exploded view showing the mechanism with its various elements so spaced that the shapes and inter-relationship of the various elements may be more clearly discerned. The

various vertical shafts and different other inter-connecting members are shown greatly exaggerated in length to permit wide spacing of the parts in the drawings. The shafts 12 are shown having at their upper ends the platens 14 and 15 constituting the record magazine and which are operated to effect discharge of the records in the magazine one by one.

Finger 19 is shown connected to disk 35 through member 19', whereby the two are rotated upon rotation of shaft 12 by means of the drag connection comprising spring 37 and member 91 on shaft 12. Adjacent disk 35 is positioned stop lever 40 with its detent 45 which cooperates with the periphery of disk 35.

The tone arm 16 is shown in the same position in which it is shown in Figs. 1 and 2 in which it rests upon the upper end of a rod 51. This rod 51 rests at its lower end on two resilient members 53 and 54 the latter of which carries a contact, which engages with an electrical contact 55 to constitute a switch in the electrical circuit of the motor which drives the turntable. The weight of the tone arm is such that, resting upon the rod 51, it bears resilient members 53 and 54 downward and thus opens the switch 54, 55 and stops the motor. This occurs after the playing of the last record in the magazine.

Handle 18 by which the phonograph is started is rigidly attached to one end of a rod 55 which has rigidly attached to its lower end a member 56 which, when rod 55 is rotated by actuation of handle 18, cooperates with the lower end of rod 51 to move it upward thus closing the motor circuit. The turntable then starts to rotate. The member 56, in its rotation also, through cam action between itself and member 57, causes longitudinal motion of member 57, thereby to engage member 24 and actuate it backward to close the clutch 21 to connect cam shaft 20 to the spindle 2 of the turntable.

This clutch 21 comprises a stationary drum 60 having a notch 70 at one point in its periphery. This notch 70 is engaged by a tooth 71 carried by means of a rocker member 72 of the shape shown in the drawings. This rocker member is pivoted for rotation about pivot 73 by which it is secured at point 74 in a disk 75 mounted rigidly on the shaft 20. One end 76 of this member 72 rides in a notch 77 in the periphery of this disk 75, and extends adjacent the teeth of a ratchet wheel 83 which forms the driving member of the clutch. The opposite end 78 of member 72 is connected by means of a spring 80 to a member 81 which is attached to the disk 75 at point 82. In this way the member 72 is biased to the open condition of the clutch in which tooth 71 engages the notch 70.

When member 24 is moved inward it engages the end 76 of member 72 rocking this member in the counterclockwise direction about member 73 thus removing the tooth 71 from the notch 70, and at the same time, moving the end 76 into engagement with the teeth of ratchet wheel 83. This ratchet wheel 83 is connected through the worm wheel 23 and worm 22 to the spindle 2 of the turntable. The ratchet 83 then drives the member 72, disk 75, and the shaft 20. After tooth 71 moves out of notch 70 on to the periphery of the drum 60 the clutch cannot be opened until at least one revolution of the shaft 20 has been completed. When this occurs the tooth 71 drops into the notch 70, moving end 76 of member 72 out of engagement with ratchet 83, and thereby opens the clutch.

During the rotation of the shaft 20, cams 26 and 27, of course, rotate. The first action is that of cam 26 which moves rod 28 upward thus lifting the tone arm 16 off from rod 51 whereupon the switch 54—55 remains closed by reason of the resilience of members 53 and 54 even though handle 18 is released by the operator. In its upward movement the tone arm hinges about a horizontal pivot 120 of hinge 121 provided on one end of member 99 carried by column 28'.

Following this action cam 27 rotates rocker member 29 and the shaft 30 in its mounting first in a counterclockwise direction, thereby actuating arm 31 backward. The upper end of this member 31 is connected by means of a link 84 to lever 34. This lever 34 is pivoted about the shaft 2 of the turntable and has its opposite ends connected through link members 85 and 86 to the bottom end of shafts 12 whereby those shafts are caused to rotate first in a clockwise direction. Lever 34 also carries a pin 87, which causes movement in a clockwise direction of a pivoted lever 88, which, in turn, carries at one end a pin 90. This pin 90 extends adjacent member 99 to which the tone arm is attached. During the clockwise movement of shafts 12 the pin 90 moves forward away from the turntable into engagement with member 99 whereby it moves the tone arm, if the tone arm is over the turntable, away from the turntable.

During the clockwise movement of shaft 12, finger 91 on the rear one of these shafts, as shown in the drawing, is carried in the clockwise direction about the shaft. This finger 91 is connected to the frame comprising disk 35, finger 19 and member 19' by means of the spring 37 and in this way this frame including disk 35 and finger 19 are caused to rotate as a unit clockwise until finger 19 engages the periphery of the bottom record of the stack. It is then stopped in 40 that position although the rotation of shaft 12 continues against the tension of spring 37 which may be very light. Disk 35 is thus positioned in accordance with the diameter of the next record to be played.

At about this time finger 92 on the rear shaft 12 engages a finger 93 the latter of which is connected through a one-way drive connection with a shaft 94 on which pawl 43 is rigidly mounted. Pawl 43, shaft 94 and finger 93 are biased to the position shown by means of a spring 95. In this position the pawl 43 engages a notch in the end of the stop lever 40. When finger 92 engages finger 93, this finger, pawl 43 and shaft 94 rotate as a unit against the tension of spring 95, pawl 43 moving out from engagement with the notch in the end of stop lever 40, whereupon lever 40 moves under the bias of its spring 42 until detent 45 engages the periphery of disk 35. Of course, the point on the periphery of disk 35 which is engaged by detent 45 is determined by the diameter of the next record to be played and thus stop lever 40 assumes a position in accordance with the diameter of the next record or, if the magazine be empty, it assumes the position in which it is shown in the drawings.

Of course, after finger 92 passes finger 93, pawl 43 snaps back into one of the notches in the end of lever 40, thereby to retain that lever in the position to which it has been actuated after disk 35 and finger 19 return to their initial position.

The rotation of shafts 12 now continues with platens 14 moving between the bottom two records of the stack. Platens 15 then move out from under the bottom record permitting it to

drop upon the turntable. The rotation of shafts 12 is then reversed by reason of the shape of cam 27 from which they are driven, whereupon platens 15 return beneath the next record in the magazine and assume the support of the stack. During this return movement, the finger 92 again engages finger 93 and this finger now moves freely about shaft 94 and permits finger 92 to pass.

10 Pin 90 is now moved away from the tone arm toward the turntable. This leaves the tone arm 16 free to be rotated by means of a spring 96 toward the turntable.

This spring 96 is connected to a tone arm return lever 97 carrying an upright member 98 which engages the forward portion of member 99 to which the tone arm is attached and which is arranged for rotation about the rod 28 and column 28'. Thus spring 96 causes clockwise movement of the tone arm return lever 97, members 98, finger 99, and tone arm 16, about shaft 28, until pawl 50, carried by the tone arm return lever 97, engages one of the notches 46, 47 or 48 in the tone arm stop lever 40. In the position 25 shown it engages notch 48 since it is assumed that the machine previously had stopped after playing the last record. Since the bottom record shown in the magazine is of small diameter, the pawl 50 will, in the operation being described, 30 engage the notch 46, and the tone arm will be moved to a position corresponding to the starting point of a small record.

Shaft 20 now completes its revolution, rod 28 is lowered by cam 26 thus lowering the tone arm 16 on to the record.

At this time the tooth 71 rides into the notch 70 in drum 60 thus opening clutch 21 and stopping the operation of the record changing mechanism.

The record is now played to its completion at which time a member 100, which is attached to member 99 on which the tone arm is mounted, engages member 24 again closing the clutch. The cycle of operation, just described, is now 45 repeated, this operation continuing until all the records have been played. Of course, after the small diameter records have been played and when the next record to be played is of large diameter, the pawl 50 engages the notch 47 because of the position occupied by lever 40, thus stopping the tone arm at the starting position of the large record. After all of the records have been played and the magazine is empty, the finger 19, in the next cycle of operations, finds itself free to move inward to the fullest extent whereupon detent 45, when moved into engagement with the disk 35, falls at the point of largest diameter of this disk. Stop lever 40 is then stopped in the position shown in the drawings whereby pawl 50, on its return movement, 50 engages in the notch 48 thus stopping the tone arm in the position shown. Then when the tone arm is lowered by cam 26 it falls upon the rod 51 and by reason of its weight, causes deflection of resilient members 53—54 opening the switch 54—55 and stopping the turntable.

To describe additionally the one way drive connection previously mentioned, between finger 93 and shaft 94 it is pointed out that this finger 93 is loosely mounted on shaft 94. A member 93' is rigidly connected to shaft 94 at its lower end and extends beneath finger 93. A pin 122 extends downward from finger 93 at one side of member 93' and a pin 123 projects upward from member 93' at the other side of finger 93. Spring 124 having one end attached to shaft 94

and its other end attached to the tail of finger 93, biases pins 122 and 123 toward each other. When finger 92 in its clockwise motion, engages finger 93 it actuates shaft 94 through engagement between pin 122 and member 93', and thereby carries pawl 43 counterclockwise. On the return movement of finger 92, finger 93 merely moves freely around shaft 94 against the spring 124.

It should also be noted that pawl 45 is connected to stop lever 40 through a spring 45' to lessen noise and improve the smoothness of the action. For the same reason a spring connection is utilized between pawl 50 and member 97.

If at any time during the playing of a record the operator decides that he does not wish to complete the playing of that record, but wishes to reject it instead, he moves handle 18 to the right as shown in both Figs. 2 and 3. This starts the record changing operation as previously described. This occurs irrespective of the position of the tone arm on the record. The tone arm is lifted, moved away from the record, a new record dropped on the turntable and the tone arm moved back to the starting position of the new record and the playing of the new record is begun.

If now, the operator decides to stop the machine he moves handle 18 to the left as shown in Figs. 2 and 3. This starts the record changing action as before. However, this leftward movement of handle 18 carries member 122, which is pivoted on the rear end of member 123 to which handle 18 is attached, to the right, its end 124 engaging stop lever 40 and operating it against its spring bias 42 to such a position that when engaged by pawl 50 the tone arm is stopped beyond the record and when lowered the tone arm falls on rod 51 opening the switch 54, 55 and stopping the machine.

Fig. 4 shows a slight modification of the stop lever 40 in which it has only notches 47 and 48, the function of notch 46 of Fig. 3 being served by means of a fixed pin, or stop post 101. This pin is so positioned that when the tone arm return lever is returned, it is stopped by pin 101 in the position corresponding to the starting position of a small record. Of course, if the next record to be played be large then it is returned until pawl 50 engages notch 47, or if the magazine be empty, until pawl 50 engages notch 48. If desired, pin 101 may be positioned to stop lever 40, rather than lever 97, at the position corresponding to a small record.

Fig. 5 shows a modification of my invention in which the clutch 21 is not operated by gradual inward movement of the tone arm but is operated only in response to increased velocity of movement of the tone arm. This is desirable because the sound groove of records may stop at different inner diameters dependent upon the length of record played with the result that the record changer may be set into operation before the record has been entirely completed. On many records the sound groove terminates in a spiral as indicated at 103 on record 102 shown in Fig. 5. This spiral leads to a concentric inner groove 104. In accordance with the modification shown in Fig. 5 the record changer is started only in response to the rapid inward movement of the tone arm as the stylus 17 traverses the spiral 103.

In this figure the member 100 which in Fig. 3 is shown as carried by the tone arm support 99, is connected to the tone arm by means of a spring 105. Thus, on the inward movement of

the tone arm, as the lower end of member 100 engages member 24' it may move it inward slightly but its inward movement is repelled by means of a member 106 which is engaged by a pin 107 carried by ratchet 83. Members 24' and 106 are rigidly attached to the pivot member 108 so that any slight movement of member 24' inward, moves the lower end of member 26 outward until its outer surface is engaged by the pin 107 on the ratchet 83 in its next rotation, which in turn moves member 106 inward and member 24' outward. This pushes member 106 back to its starting position, restoring member 24' to its initial position and retaining the clutch open. When the stylus however, reaches the spiral groove 103, member 104 then bears against member 24' sufficiently to move member 106 completely across the path of movement of pin 107 so that it is not engaged by pin 107. Member 24' thus moves end 76 of member 72 into the teeth of the ratchet and closes the clutch, whereupon shaft 20 and its cams are rotated through one revolution.

Fig. 6 shows in greater detail the shape of member 106 and its relation to the ratchet 83 and the pin 107. It will be seen that if member 106 is moved to the left only slightly it will be engaged by pin 107 and actuated back to its initial position. If it is actuated across the path 109, however, of the pin 107 then no such action occurs and the clutch may be closed by engagement of 24' with member 76.

Fig. 7 shows a further modification of my invention in which means are provided to move the tone arm into the initial groove of the record after it has been lowered onto the record. In this figure, as in other figures, the tone arm is hinged to the member 99 at hinge 121. The member 99 is rigidly attached to sleeve 28' about shaft 28. This sleeve is mounted for longitudinal movement through a bushing 123 from a position corresponding to that shown to an upper position in which stop 124, mounted on its lower end, engages the chassis 4. Since the tone arm is supported on rod 28 at a point intermediate its ends upward movement of rod 28 tends to lift both ends of the tone arm including hinge 121. This also lifts member 99 and sleeve 28' until stop 124 engages the chassis. Hinge 121 then opens, the opposite end of the tone arm raising and pivoting at hinge 121.

In the upward position of member 99, when the tone arm is moved by pin 90 outward away from the turntable and into engagement with member 98 carried by the tone arm return lever, its forwardly projecting finger 99' becomes latched to upright 98 by means of a hook 111 attached to the upper end thereof. The tone arm and member 98 are now pushed further outward by the pin 90 beyond the position shown in Fig. 3 and after the changing of the record, are again moved inward by means of the spring 96 until stopped by stop lever 40. Any tendency for the tone arm 16 to swing farther inward about pivot rod 28, by reason of its own inertia after pawl 50 engages the stop lever 40, is prevented by the hook 111. Now, when rod 28 is lowered, member 99 is also lowered thereby releasing finger 99' from hook 111. A very slight spring 112 attached to member 98 now bears against finger 99' thus giving the tone arm a slight inward tendency so that it moves gently into the first groove of the record after it has been dropped upon the record at a point beyond the grooved portion thereof.

Fig. 8 shows a further modification of my invention incorporating means for moving the tone

arm into the initial groove of the record but in which the number of parts above the chassis is reduced. The chassis 4 is indicated in Fig. 8 having the column 130 rigidly attached thereto. On the top of this column rides member 99 to which the tone arm 16 is hinged at 121 as in Fig. 7. Sleeve 28' extends through this column 130 and has member 99 attached rigidly to its upper end. The sleeve 28' is somewhat longer than column 130 and below the lower end of the column 130 sleeve 28' carries a disk 131 having two projections 132 and 133 to the latter of which is attached upward projecting member 134 presently to be referred to.

About column 130, below the chassis is a sleeve 135 carrying a disk 136 having a horizontal projection 137, an aperture 138 adapted to receive projection 134, and adjacent thereto, a downward projection 139 somewhat shorter than projection 134.

Beneath disk 131 and about rod 28 is mounted the tone arm return lever 97 having member 98 projecting upward therefrom to cooperate with projection 137 tending to move it to the right under influence of spring 96.

Further details of this construction may better be understood from a description of its operation.

At the beginning of the record changing operation rod 28 is moved upward to lift the tone arm as described in connection with the other figures. Since it engages the tone arm at an intermediate point its upward movement also lifts member 99 and sleeve 28' until projection 134 engages the lower surface of disk 136. Hinge 121 then opens and the lifting of the tone arm is completed.

Pin 90 is now moved to the right as described in connection with the other figures. It engages projection 132 of disk 131 moving disk 131 counterclockwise until projection 134 enters aperture 138. This movement causes outward rotation of the tone arm over the record. When member 134 engages member 139, or enters aperture 136 disk 136 is also rotated counterclockwise.

Its projection 137 engages member 98 carried by tone arm return lever 97 and moves this lever counterclockwise against spring 96.

Before member 134 engaged member 139, or entered aperture 138, it engaged the end of a small spring, indicated on the drawings as a hairpin spring 140, suitably carried by disk 136 and placed it under stress tending to produce opposite rotations of disks 136 and 131.

After the record to be played is discharged upon the turntable pin 90 moves to the left. The tone arm return lever then moves clockwise under its spring bias, member 98 rotating disk 136 and also disk 131 which is now locked to disk 136 by member 134 projecting into aperture 138, until the return lever 97 is stopped by engagement with the tone arm stop lever as described in connection with the other figures. When this occurs the tone arm is prevented from further inward movement under its own inertia by reason of engagement of projection 134 with aperture 138.

When the tone arm is lowered sleeve 28' lowers moving disk 131 downward and withdrawing projection 134 from aperture 138. Spring 140 now tends to produce a further inward movement of the tone arm just sufficient to move the stylus gently into the first groove of the record.

Of course, the component parts of Fig. 8 are shown distorted in form and displaced for clearness of description and illustration. In actual form the unit is very compact, mounted below the chassis and out of view.

My invention, it will be seen, is extremely simple in its structure and operation and is assembled into a very compact unit as shown in Fig. 1. While in Fig. 1 I have shown certain of the operating mechanism above the chassis 4 it will be understood that if desired practically the entire mechanism may be placed beneath the chassis for improvement in the appearance of the finished device. If desired, all of the parts below dotted line 130' of Fig. 3 may be placed beneath the chassis and out of sight, the vertical members extending across this line projecting through properly shaped holes in the chassis.

While I have shown particular embodiments of my invention, it will, of course, be understood that I do not wish to be limited thereto since different modifications may be made therein without departing from the spirit and scope of my invention. I contemplate by the appended claims to cover any such modifications as fall within the true spirit and scope of my invention.

What I claim as new and desire to secure by Letters Patent of the United States is:

1. In combination, a turntable, a record magazine, comprising upright shafts adjacent said table having platens arranged to support a stack of records over said table, and when rotated to discharge the bottom record of said stack onto said table, a frame secured about one of said shafts having a finger rigidly mounted thereon and normally positioned away from said stack, means responsive to rotation of said one shaft to rotate said finger about the axis of said shaft as a pivot into engagement with the periphery of the next record to be discharged irrespective of the diameter of said next record to be discharged whereby said rotation about said axis of said shaft as a pivot is stopped upon engagement of said next record and at a position corresponding to the diameter of said next record, a tone arm stop device, means selectively responsive to the position of said frame when rotation of said finger is stopped by engagement with said record to position said tone arm stop device in either one of a plurality of positions in accord with the position of said frame, a tone arm, and means operative after said bottom record is discharged to move said tone arm to a position determined by the position of said tone arm stop device.

2. In combination, a turntable, a record magazine comprising upright shafts adjacent said table having platens arranged to support a stack of records over said table, and when rotated to discharge the bottom record of said stack onto said table, a frame secured about one of said shafts having a finger extending therefrom normally positioned away from said stack, means responsive to rotation of said shaft to rotate said frame and finger about the axis of said shaft as a pivot until said finger engages with the periphery of the next record to be discharged irrespective of the diameter of said next record whereby said rotation of said frame about said axis of said shaft as a pivot is stopped upon engagement of said next record and at a position corresponding to the diameter of said next record, a tone arm stop device, means to position said tone arm stop device in either of a plurality of positions, means to select said positions in response to the position of said frame when said rotation is stopped by engagement of said finger with said next record whether said next record be large or small, and means to maintain the position of said

tone arm stop device after said next record has been discharged.

3. In combination, a turntable, a record magazine, comprising upright shafts adjacent said table having platens arranged to support a stack of records over said table and when rotated to discharge the bottom record of said stack onto said table, a frame secured about one of said shafts having a finger extending therefrom normally positioned away from said stack, means responsive to rotation of said shaft to rotate said finger about the axis of said shaft into engagement with the periphery of the next record to be discharged whether said record be large or small, a resilient drive connection between said shaft and said finger whereby said finger stops upon engagement with the periphery of said next record while said rotation of said shaft continues, a tone arm stop device, and means selectively responsive to the position of said finger when engaging said next record to position said tone arm stop device in accord with the diameter of said next record.

4. In combination, a tone arm, a turntable, a record magazine having discharge mechanism, said mechanism being rotatable in one direction about an axis to discharge a record and in the other direction to return to initial position, an index member, means comprising a resilient connection between said mechanism and said index to rotate said index about said axis as said mechanism is rotated about said axis, said index member being positioned and arranged to engage the periphery of the record to be discharged during said rotation of said mechanism in the first direction and to be stopped thereby in a position in its rotation about said axis dependent on the diameter of the next record to be discharged and then to return to its initial position in response to rotation of said mechanism in the opposite direction, a tone arm stop lever, means to operate said tone arm away from playing position, means operable after said record has been discharged to operate said tone arm toward playing position and against said stop lever, and means to position said stop lever in accordance with the position of said index member when it engages said periphery, whereby said stop lever is engaged at one point or another by said tone arm, said lever being shaped to stop said tone arm at a position corresponding to the diameter of said record.

5. In combination, a turntable, having a vertical shaft, two vertical shafts having platens thereon arranged to support a stack of records over said table, and to discharge said records one by one upon predetermined reciprocation of said shafts, a lever pivoted about said turntable shaft and connecting said two shafts for simultaneous reciprocation, a tone arm, means responsive to predetermined movement of said tone arm to cause one reciprocation of said lever and reciprocation of said two shafts to discharge a record, a tone arm stop device, means responsive to movement of said lever to move said tone arm away from said record, and to position said stop device in accordance with the diameter of the next record to be discharged, and means to return said tone arm to a position determined by said stop device.

6. In combination, a turntable, a plurality of vertical shafts near said table having horizontal platens arranged thereon to support a stack of records over said table, said platens being arranged upon predetermined rotation of said shafts to discharge the bottom record in said

stack, a lever arranged for oscillation about a pivot and having opposite ends connected to said shafts for simultaneous rotation thereof, a tone arm, means responsive to predetermined movement of said tone arm to cause one oscillation of said lever, a tone arm stop device, means responsive to movement of said lever in one direction to move said tone arm away from said turntable and to operate said stop device to a position corresponding to the diameter of the next record to be discharged, and means to move said tone arm to a position determined by said stop device.

7. The combination, a turntable, a record magazine having record discharge mechanism arranged to discharge one record on each operation thereof, a cam, means responsive to operation of said mechanism to position said cam in response to the diameter of any record to be discharged, a tone arm, a tone arm stop lever, means to move said tone arm toward record playing position and into engagement with said stop lever after said record has been discharged, means operable before said record is discharged to position said stop lever in response to the position of said cam thereby to stop said tone arm in a corresponding position, whereby said lever is engaged by said tone arm at one point or another dependent upon the diameter of said record, and said stop lever being so shaped that said tone arm is stopped in varying positions in response to the diameter of the next record to be played.

8. In combination, record discharge device having a shaft arranged for reciprocal rotation to discharge a record, a cam driven from said shaft and having a stop finger arranged to engage the periphery of the record to be discharged to stop movement of said cam, a tone arm stop lever biased for movement against said cam, means to restrain movement of said stop lever until said finger engages said periphery, means to release said restraint after said finger engages said periphery whereby said lever moves under its bias to a position determined by said cam in accordance with the diameter of the record discharged, a tone arm, means to move said tone arm over the discharged record, and means carried by said tone arm to engage said stop lever and stop said tone arm at a position determined thereby.

9. In combination, record discharge device having a shaft arranged for reciprocal rotation to discharge a record, a cam driven from said shaft and having a stop finger arranged to engage the periphery of the record to be discharged to stop movement of said cam, a tone arm stop lever biased for movement against said cam, a pawl device normally biased into engagement with said lever to restrain it against movement under its bias, a finger carried by said shaft, and arranged at a predetermined point in the rotation of said shaft to actuate said pawl device from engagement with said lever against its bias and then to release said pawl device, whereby said lever moves against said cam and is again restrained by said pawl device in a new position corresponding to the position of said cam, a tone arm, means to move said tone arm over the discharged record, and means carried by said tone arm to engage said stop lever and stop said tone arm at a position determined thereby.

10. The combination, in a record changing phonograph in which records of different diameter are indiscriminately stacked in a magazine and played successively, a turntable, means operable after a record has been discharged from

the magazine to said table to move said tone arm toward said record, fixed means to stop said tone arm in a position corresponding to records of one diameter, a stop lever having two positions, and means controlled by the bottom record of said magazine to move said lever to one of said positions in response to a record of a different diameter, and to the other of said positions in response to an empty magazine, said first means operating to move said tone arm against said stop lever thereby to stop said tone arm in a position corresponding to the instant position of said stop lever.

11. The combination, in a record changing phonograph in which records of different diameter are indiscriminately stacked in a magazine and played successively, a turntable, means operable after a record has been discharged from the magazine to said table to move said tone arm toward said record, fixed means to stop said tone arm in a position corresponding to records of one diameter, a stop lever having two positions, means to move said lever to one of said positions in response to a record of a different diameter, and to the other of said positions in response to an empty magazine, said first means operating to move said tone arm against said stop lever thereby to stop said tone arm in a position corresponding to the instant position of said stop lever, means to lower said tone arm after it has been stopped, and means responsive to lowering of said record in the position corresponding to an empty magazine to stop said phonograph.

12. The combination, in a record changing phonograph, in which records of different diameter are indiscriminately stacked in a magazine and played successively, a turntable, means operable after a record has been discharged from the magazine to said table to move said tone arm toward said record, a tone arm stop lever having at least three positions, means to move said lever to one or another of two of said positions dependent respectively upon the diameter of the next record to be discharged from said magazine and to move said lever to a third of said positions in response to an empty magazine, means subsequently to stop said tone arm in a position corresponding to the position of said stop lever, whereby said tone arm stops in a position corresponding to the diameter of a record to be played or in a position corresponding to an empty magazine, means to lower said tone arm, and means to stop said phonograph in response to lowering of said tone arm in the position corresponding to an empty magazine.

13. The combination, in a record changing phonograph in which a tone arm is raised and moved outward away from the played record after completion thereof, and is substantially moved inward and lowered over a new record, a tone arm return lever biased continuously to the inner position of said tone arm and positioned to be moved against its bias by engagement with said tone arm in its outward movement, said lever operating under its bias to move said tone arm inward, a stop for said return lever, means to latch said tone arm to said return lever to prevent movement thereof under its own inertia when said return lever engages said stop, and means to unlatch said tone arm from said return lever when said tone arm is lowered.

14. The combination in a record changing phonograph in which a tone arm is raised and moved outward away from the played record after completion thereof, and is subsequently moved inward and lowered over a new record, a tone arm return lever biased to the inner position of said tone arm and positioned to be moved against its bias by engagement with said tone arm in its outward movement, said lever operating under its bias to move said tone arm inward, a stop for said return lever, means to latch said tone arm to said return lever to prevent movement thereof under its own inertia when said return lever engages said stop, and means to unlatch said tone arm from said return lever when said tone arm is lowered, and a spring carried by said return lever engaging said tone arm to cause inward movement thereof into the first groove of the record after said tone arm is lowered.

15. In combination, a turntable, a record magazine having upright shafts adjacent said table having platens arranged to support a stack of records over said table, and when rotated to discharge the bottom record of said stack onto said turntable, a cam mounted to rotate about the axis of one of said shafts, said cam having a finger normally positioned away from said stack, means responsive to rotation of said shaft and platens yieldably to rotate said cam and finger about said axis of said shaft until said finger engages the next record to be played, said finger being positioned and arranged to engage said next record and to be arrested in its movement about the axis of said shaft thereby while rotation of said platens continues, whereby said cam is selectively positioned in accord with the diameter of any record next to be played, a tone arm, means to move said tone arm first outward away from said records and then inward toward said records, and means to stop said inward movement of said tone arm at a position determined by the position of said cam.

16. In combination, a turntable, a record magazine having upright shafts adjacent said table having platens arranged to support a stack of records over said table, and when rotated to discharge the bottom record of said stack onto said turntable, a cam mounted to rotate about the axis of one of said shafts, said cam having a finger normally positioned away from said stack, means responsive to rotation of said shaft and platens to rotate said cam and finger about said shaft in one direction until said finger is arrested by engagement with the next record to be played and to return said cam and finger to initial position in response to return movement of said shaft, whereby said cam, during the interval of forward movement of said shaft after said finger is arrested, occupies a position corresponding to the diameter of the next record to be played, a tone arm stop lever biased against said cam during said interval, means to latch said lever in position determined by said cam during said interval, a tone arm, and means to move said tone arm outward away from said records and then inward toward said records and to stop said inward movement at a point determined by the position in which said stop lever is latched.
